AUTOMATIC BAG STRINGING NEEDLE

Edward E. West, Richmond, Va.

Application June 4, 1940, Serial No. 338,814

9 Claims. (Cl. 112—173)

The present invention relates to means for automatically directing the needles of a bag stringing machine through the hems of a bag.

The principal object of this invention is the provision of means, associated with the stringing needles of the bag stringing machine of my pending application, Serial No. 250,223 filed January 10, 1939, for automatically directing the needles into and through the hems of a bag and passing draw strings therethrough.

A further object is to provide means, cooperating with a pair of needles of a bag hem stringing machine, for automatically directing the points of the needles into and passing the needles and draw strings through the hems of the bag.

Another object is the provision of means, cooperating with a pair of stringing needles of a bag hem stringing machine, for automatically changing the longitudinal axis of the needles whereby the needles are caused to form their own openings in and to enter into the ends of and to pass through the hems of a bag for stringing the same.

These and other objects and advantages will be apparent as the following specification is considered with the accompanying drawings wherein:

Figure 1 is a plan view of the bag stringing needles, operating structure therefor, and the means for deflecting the points of the needles into the ends of a bag hem;

Figure 2 is an enlarged end view of the stringing needles and the connecting rock shafts and levers for deflecting the points of needles, and showing the needle engaging levers in normal inoperative position;

Figure 3 is an end view, similar to Figure 2, with the needle engaging levers rocked to operative position for deflecting the needles into hem entering position;

Figure 4 is a diagrammatic view showing the needles deflected and entering the hems of a bag;

Figure 5 is a diagrammatic view showing the needles entered into the bag hems and in the position assumed after having been released by the needle deflecting members;

Figure 6 is a plan view of a modified form of needle deflecting means;

Figure 7 is an end view of the modified form of needle deflecting means shown in Figure 6.

Referring more particularly to the drawings, wherein like reference characters designate similar parts throughout the several views, the numeral 1 denotes generally a stringing needle

carriage of a bag stringing machine, for applying draw strings to the hems of tobacco bags and the like, described and illustrated in my pending application, Serial No. 250,223, filed January 10, 1939. The stringing needle carriage 1 comprises a relatively flat, substantially rectangular needle saddle or plate 2, slidably mounted between a pair of spaced longitudinal guide tracks 3, suitably secured by screws or the like 4 to the upper face of a flat supporting plate 5, in turn mounted on the top frame of a bag stringing machine, not shown.

The inner ends of two longitudinally extending resilient hollow needle sleeves 6 are rigidly supported in a block or plate 7, secured to the top of the needle saddle, and two resilient pointed needles 8 are arranged within the sleeves 6 for reciprocating movement relative thereto. Reciprocation of the needles 8, through the sleeves 6, as presently described, moves the needle points 9 away from the forward ends of the needle sleeves 6 to provide gaps or eyes for the insertion of strings, not shown, therein. When the needles 8 are moved to closed or string gripping position, the strings are clamped or gripped between the rear ends of the needle points 9 and the ends of the needle sleeves 6. The forward ends of the needle sleeves and needle eyes 9 slidably extend through suitable guide openings 10, in upstanding block 11 on plate 5, and are thus guided during their forward and return strokes through the hems 13 of a bag 12, supported on a pair of vertically disposed bag holding arms 14, of a rotating turret head, not shown. The rear ends of the needles 8 are fixed within a small block 16, mounted on the needle saddle 2 and connected by a pair of spring tensioned pins 17 to the saddle block 7, for slight sliding movement relative thereto. The block 16 is forwardly actuated, against the tension of springs 18 mounted on the pins 17, by any suitable means such as a small cam 19 carried by a crank 20, supported in a journal block 21 secured to the rear end of saddle 2. The other end of crank 20 carries a cam 22 for engaging with two stops 23, secured to one of the guide tracks 3, adjacent opposite ends thereof.

The needle saddle 2 is reciprocated forwardly and rearwardly, between the guide tracks 3, to move the needles through the hems 13 of the bag 12, during the stringing operation, by any suitable means, such as a vertically disposed lever 24 pivotally connected at its upper end to an arm 25, in turn pivoted to the rear end of the needle saddle 2. The lever 24 is fulcrumed to

the lower portion of the machine frame and carries a roller, not shown, which travels in a cam groove in the face of a cam, not shown, mounted on a driven shaft, also not shown. The needle saddle 2 is reciprocated back and forth, between the guide tracks 3, and, at predetermined points in the travel of needle saddle 2, the block 16 is engaged by cam 19 on crank 20 and the needles 8 are thus moved forwardly through their sleeves 6 a sufficient distance to provide the string gaps, between the ends of the sleeves 6 and points 9, within which the ends of the stringing threads are received.

When a bag 12 is supported in vertical stringing position on the vertically disposed pair of bag holding arms 14, with the hems 13 in line with the pointed heads 9 of the needles 8, it is necessary to provide means for directing the needle points 9 slightly inwardly towards each other in order to insure of the points 9 forming openings in the ends of the hems to permit of the needles passing into and through the hems.

In the preferred form of needle deflecting structure illustrated in Figures 1 to 3, a pair of opposed substantially L-shaped levers 26, connected together at their lower ends by a spring 40, are pivotally mounted on a block 27, secured to the inner end of plate 5, adjacent needle guide block 11. The upper ends of the levers 26 carry rollers or the like 28 for engagement with the outer sides of the needles, as the levers are rocked in opposed directions, as hereinafter described. Downwardly depending adjustable screws 29, mounted in the levers 26, engage with the top face of a plate 30, pivotally mounted on the inner end of a rock arm 31. The outer end of rock arm 31 is fixed to the inner end of a longitudinally extending rock shaft 32, journaled in suitable bearing plates or journals 33 secured to the underside of plate 5. The curved lower end of a rock arm 34, extends substantially vertically through an aperture 35 in plate 5, and is secured to the outer end of shaft 32. A depending screw 36 on the upper end of the arm 34 is adapted to engage with a tapered cam piece 37, secured to the top face of the needle saddle 2. As the needle saddle 2 is moved forwardly, to enter the needles through the hems of the bag, the tapered face of the cam piece 37 engages with and elevates the screw 36, of the rock arm 34. This movement of the rock arm 34 in turn rocks shaft 32 and rock arm 31, in a clockwise direction, viewing Figs. 2 and 3 and raises the plate 30 against the lower ends of the screws 29 on the levers 26 thus rocking the latter inwardly against the tension of spring 40 and causing the rollers 28, on the upper ends of the levers 26 to engage with the sides of and deflect the outer ends of the resilient needles inwardly towards each other, it being understood that the needles are for this purpose formed of resilient material such as steel or the like. When the needles are deflected or bent inwardly, at their outer ends, the points 9 thereof pierce the cloth of and enter the ends of the bag hems 13, as shown in Figure 4. As the inwardly bent or deflected points 9 of the needles enter the ends of the bag hems, the continued forward travel of the needle saddle 2 carries the cam 37 beyond and out of engagement with the depending screw 36 on the upper end of the rock arm 34, whereby the rock arm 34 is lowered or dropped to its normal position. The lowering of rock arm 34 causes the shaft 32 and rock arm 31 to be rocked in the opposite or counterclockwise direction, viewing Figures 2 and 3, thus lowering plate

30, carried on the end of arm 31, so that the rollers 28 on upper ends of the L-shaped levers 26 are swung outwardly by the action of spring 40 in opposed directions about their pivots, to their normal vertical positions and out of engagement with the sides of the needles. As the pressure of the rollers 28 is removed from the needles, which have formed openings in and entered the bag hems, the needles automatically spring outwardly to their normal positions, parallel to each other, and continue to pass straight through the hems on a straight line, as shown in Figure 5. Thus, it will be noted that, by virtue of the connecting rock shafts and levers, the points 9 of the needles are caused to automatically form their own openings in the bag hems and to pass therethrough, without snagging or otherwise forming openings in the ends of the hems for the needles to enter. In other words, as the points of the needles form their own openings in the hems, there is no need to employ separate or independent hem opening or snagging means for opening the hems to permit of the needles entering therethrough.

A modification of my needle deflecting device is illustrated in Figures 6 and 7. In this embodiment, a laterally projecting, beveled or rounded cam piece 41, secured to the needle saddle 2, is adapted to cooperate with a cam face 43 on the outer end of a lever 42 pivotally mounted, intermediate its ends, on one of the saddle guide tracks 3. The inner end of the lever 42 carries a downwardly and laterally extending arm 44 which engages with the lower end of a vertical arm 45, pivoted as at 46, to the edge of the plate 5. Mounted in the upper ends of the arms 44 and 45 are a pair of inwardly extending, aligned, adjustable screws 47, which engage with the sides of the needles 6. Upon forward travel of the needle saddle 2, the cam piece 41 contacts the cam face 43 and swings the inner end of the lever 42 outwardly, whereby the arm 44, on the outer end thereof, is swung inwardly against the lower end of the arm 45. This pivotal action of the lever 42 swings the screws 47, on the upper ends of arms 44 and 45, inwardly and presses the same against the sides of the needles 6 whereby the resilient needles are deflected or bent inwardly. In this position of the needles, the points 9 thereof pierce the material of the bag hems 13 and form openings therein for the needles to enter. The continued forward travel of the needle saddle 2 carries the cam piece 41 beyond and out of engagement with the cam face 43, on the inner end of lever 42, so that pressure of the screws 47 against the sides of the needles 6 is relieved and the needles automatically spring outwardly to their normal positions, parallel to each other, and continue to pass straight through the bag hems.

It is to be understood that the provision of means for automatically causing stringing needles to form their own openings in and enter through the hems of a bag is a new advancement in the bag manufacturing art. While I have shown and described a preferred form and a modification of my invention, it is to be further understood that numerous changes and improvements may be made without departing from the scope and spirit of the appended claims.

Having thus described my invention, what I claim is:

1. In a device of the character described for stringing hemmed bags, a pair of needles for stringing the bag hems, supporting means for said needles and operating means for reciprocating

ing said needles through the bag hems, a pair of members pivotally mounted adjacent the sides of said needles, means on said members adapted to momentarily engage the sides of said needles, and means engageable with said members for actuating said members, and means on said needle supporting means for momentarily moving said means against the sides of said needles for bending the latter in opposed directions for forming openings in the bag hems and entering the needles therethrough.

2. In a device of the character described for stringing hemmed bags, a pair of needles for stringing the bag hems, supporting means for said needles and operating means for reciprocating said support and moving said needles through the bag hems, a pair of members pivotally mounted adjacent the sides of said needles and having means thereon adapted to momentarily engage the sides of said needles, means engageable with said members for actuating said members, and means on said needle support cooperating with the said needle operating and engaging members for momentarily moving said members and needle engaging means thereon against the sides of said needles to bend the latter in opposed directions and form openings in the bag hems through which the needles enter.

3. In a device of the character described for stringing hemmed bags, a pair of substantially resilient needles for stringing the bag hems, supporting means for said needles and operating means for reciprocating said support and moving the needles through the bag hems, a pair of members pivotally mounted adjacent the sides of said resilient needles, means on said members adapted to momentarily engage the sides of said needles, and means on said needle supporting means cooperating with and for actuating said members for moving the means thereon momentarily against the sides of said needles to deflect the latter in opposed directions to form openings in the bag hems, and means for moving said means out of engagement with and releasing the needles to permit of the same to pass through the hems.

4. In a device of the character described for stringing hemmed bags, a pair of substantially aligned parallel resilient needles for stringing the bag hems, supporting means for said needles and operating means for reciprocating said support and moving the needles through the bag hems, a pair of members pivotally mounted adjacent the sides and outer ends of said needles, means on the upper ends of said members adapted to engage the sides of said needles, and means on said needle supporting means cooperating with and for actuating said members and moving and pressing said needle engaging means against the sides of said resilient needles to deflect the points of the needles inwardly out of alignment to form openings in the bag hems, and resilient means for moving said means out of engagement with and permitting of the needles springing back into alignment and passing through the hems.

5. In a device of the character described for stringing hemmed bags, a pair of needles for stringing the bag hems, supporting means for said needles and operating means for reciprocating said support and moving said needles through the bag hems, a pair of levers pivotally mounted adjacent the sides of said needles and having means on the upper ends thereof adapted to engage the sides of said needles, a rock arm

engageable with said levers for actuating said levers, and means on said needle support cooperating with said rock arm for moving said arm against said levers and moving the levers and needle engaging means thereon in opposed directions against the sides of said needles to bend the needles and form openings in the bag hems through which the needles enter.

6. In a device of the character described for stringing hemmed bags, a pair of needles for stringing the bag hems, supporting means for said needles and operating means for reciprocating said support and moving said needles through the bag hems, a pair of levers pivotally mounted adjacent the sides of said needles and having means on the upper ends thereof adapted to engage the sides of said needles, resilient means connecting said levers, a rock arm engageable with the lower ends of said levers for actuating said levers, and means cooperating with said rock arm and engageable with a cam means on said needle support for moving said rock arm against said levers and moving the levers and needle engaging means thereon in opposed directions against the sides of said needles and bending the needles to form openings in the bag hems through which the needles enter.

7. In a device of the character described for stringing hemmed bags, a pair of needles for stringing the bag hems, a supporting plate, and supporting means for said needles slidably mounted on said plate, operating means for reciprocating said supporting means and moving said needles through the bag hems, a pair of levers pivotally mounted on said plate adjacent the sides of said needles and having rotatable means on the upper ends thereof adapted to engage the sides of said needles, resilient means connecting the lower ends of said levers, a rock arm pivotally mounted on said plate and having means on the end thereof for engaging the lower ends of said levers for actuating said levers, a cam means on said needle supporting means, and means cooperating with said rock arm and engageable with said cam means during the sliding movement of said needle supporting means for rocking said rock arm against said levers and moving said levers against the sides of said needles and bending the needles to form openings in the bag hems through which the needles enter.

8. In a device of the character described for stringing hemmed bags, a pair of needles for stringing the bag hems, a supporting plate, slideable supporting means on said plate for said needles and operating means for reciprocating said supporting means and moving said needles through the bag hems, pivotally mounted means on said plate having an arm on one end thereof, a lever pivotally mounted on said plate adjacent said arm, means on the upper ends of said arm and lever adapted to engage the sides of said needles, and means on the arm carried by said pivoted means for moving said pivoted lever, cam means on said needle supporting means engageable with said pivotally mounted means for simultaneously actuating said arm and lever and moving the means on the upper ends thereof in opposed directions against the sides of and bending said needles to form openings in the bag hems through which the needles enter.

9. In a device of the character described for stringing hemmed bags, a pair of needles for

stringing the bag hems, a supporting plate, slideable supporting means on said plate for said needles and operating means for reciprocating said supporting means and moving said needles through the bag hems, a longitudinal arm pivotally mounted on said plate having a downwardly depending arm on one end thereof adjacent the side of said needles, a vertical lever pivotally mounted on said plate opposite said downwardly depending arm and adjacent the side of said needles, adjustable means on the upper ends of said downwardly depending arm and lever

adapted to engage the sides of said needles, and means on the lower end of said downwardly depending arm for engaging with and moving the lever, cam means on said slideable needle supporting means engageable with one end of and moving said longitudinal arm for simultaneously actuating said downwardly depending arm and lever and moving the means on the upper ends thereof in opposed directions against the sides of and bending said needles to form openings in the bag hems through which the needles enter.

EDWARD E. WEST.
